UNITED STATES PATENT OFFICE.

PERCY E. SCOTT, OF PHILADELPHIA, PENNSYLVANIA.

GAME-COUNTER.

No. 893,018.

Specification of Letters Patent.

Patented July 14, 1908.

Application filed November 17, 1906. Serial No. 343,818.

To all whom it may concern:

Be it known that I, PERCY E. SCOTT, a subject of the King of Great Britain, residing at Philadelphia, county of Philadelphia, and 5 State of Pennsylvania, have invented a certain new and useful Improvement in Game-Counters, of which the following is a specification.

My invention relates to a new and useful 10 improvement in game counters, and is especially adapted for recording the various happenings in the playing of bridge whist, and has for its object to provide a simple and effective counter for this purpose.

15 With these ends in view, this invention consists in the details of construction and combination of elements hereinafter set forth and then specifically designated by the claims.

In order that those skilled in the art to 20 which this invention appertains may understand how to make and use the same I will describe its construction in detail, referring by letter to the accompanying drawing forming a part of this specification, in which—

25 Figure 1 is a plan view of my improved game counter. Fig. 2, an edge view, the same being sectioned upon the line $x-x$ of Fig. 1. Fig. 3, a section at the line y of Fig. 2.

30 In carrying out my invention as here embodied, A represents a board, which may be made of any suitable material, having upon the face thereof the circular bands B and B' divided into 50 spaces, each indicated by 35 even numbers from naught to ninety-eight.

C and C' represent pointers pivoted at the center of the bands by the screws D, and beneath each of the pointers is located a block of rubber E or other compressible material 40 set in a recess formed in the board, and upon the top of this rubber block is placed a metal washer F so as to add a certain amount of friction to the pointer but prevent its being accidentally moved, while permitting it to 45 be moved around the band from space to space when occasion requires. These bands and pointers are for indicating the totals.

G, G', H and H' are circular bands, two located above each of the bands B and B', 50 divided into fifteen and twenty-one spaces respectively, each of the spaces in the bands G and H being indicated by even numbers from naught to twenty-eight, and in the bands G' and H' these spaces are indicated 55 by hundreds from naught to two thousand. At the center of each of these last named cir-

cular bands is pivoted a pointer I in the same manner as just described in connection with the pointers C and C' and for the same purpose. These pointers and bands being intended to register the number of points after each deal.

The bands G and H and their pointers are for registering the points made in the game, while the bands G' and H' and their pointers 65 are for registering the totals. The idea being that when the pointers C and C' have been moved up to zero, which indicates one hundred points, then the pointers G' and H' are moved one space to transfer the register 70 from the bands B or B' to the pointers G' or H'.

At each of the two corners of the board beneath the bands B and B' are semi-circular bands J and J', divided into nine spaces indicated by numbers from zero to eight, and 75 pointers K and K' are pivoted to the board in the same manner as that described in connection with the pointers C and C' so as to register the rubbers upon these semi-circular 80 bands. Two pointers L and L' are pivoted to the edge of the board in the same manner as described in connection with the other pointers, and are intended to indicate when a game is won by being turned up, and prior 85 to this these pointers are supposed to lie parallel with the edges of the board. The board is divided into two halves by the central line M or other demarcation, and one side is indicated by the word "we" and the other by 90 the word "they", so that each set of players may keep their score upon a duplicate set of indicators, as will be readily understood.

Heretofore it has been customary in keeping the score in bridge whist to write the different points down as they are made, and this occasions considerable confusion and loss of time, as it requires calculation to determine where each set of players stand, whereas, by the use of my improved counter, 95 a player at any stage of the game by simply observing the different pointers knows exactly where they stand, how many rubbers have been made, how many points, what the total score is and how many points are yet 100 to be made.

Having thus fully described my invention, what I claim as new and useful, is—

A game counter embodying a board, said board being divided into two equal sections 110 each of which contains therein, a large central ring, two smaller rings above the large

ring, and a semi-circular band in the outer lower corner of each section, a pointer for each ring, and a pointer for each band, a screw for holding each pointer in place, a block of rubber countersunk in the outer face of the board, a metal washer bearing against the outer face of the rubber block and against the under face of the pointer, said screw having its free end extending in said board and its body extending through said pointers, blocks of rubber, and metal washers to simultaneously hold each in its respective position, and a side pointer for each section ar-

ranged on the outer side edges at the board's ends, said side pointers being adapted to be turned so that their free ends extend beyond the outer face of said board at right angles thereto.

In testimony whereof, I have hereunto affixed my signature in the presence of two 20 subscribing witnesses.

PERCY E. SCOTT.
